UNITED STATES PATENT OFFICE.

WILLIAM J. PUGH, OF MUSCATINE, IOWA, ASSIGNOR TO THE WALTER AUTOMATIC AIR COUPLER COMPANY, OF CHARLESTON, WEST VIRGINIA.

AUTOMATIC AIR AND STEAM BRAKE COUPLING.

SPECIFICATION forming part of Letters Patent No. 601,905, dated April 5, 1898.

Application filed June 29, 1897. Serial No. 642,875. (No model.)

To all whom it may concern:

Be it known that I, WILLIAM J. PUGH, of Muscatine, in the county of Muscatine and State of Iowa, have invented certain new and useful Improvements in Automatic Air and Steam Brake Couplings; and I hereby declare that the following is a full, clear, and exact description thereof, reference being had to the accompanying drawings, which form part of this specification.

This invention is an improved automatic coupling for fluid-pressure brakes and steam-heating systems of railway-cars; and its object is to provide a coupling reliable in operation, which will perfectly couple or uncouple the fluid-pipes without manual handling, substantially like the automatic draft-couplings, will effectively shut off the air when the cars are uncoupled, and will in case of accidental breakage or pulling apart of the cars or couplings throw open the valves, so as to apply the brakes, and thus warn the trainmen of the accident and prevent running away of the car or train.

The invention therefore embraces some broadly new features of construction and in addition thereto other minor details of construction and combinations of parts, all of which will be fully understood from the following description and claims in connection with the accompanying drawings, in which—

Figure 1 is a side elevation of the automatic fluid-pressure couplings suspended in position beneath a Janney type of draft-coupling and all properly coupled. Fig. 2 is an enlarged transverse horizontal section through the fluid-pressure couplings coupled on line 22, Fig. 1. Fig. 3 is a similar section through the same uncoupled. Fig. 4 is a vertical section on line 44, Fig. 3. Fig. 5 is a horizontal section of one of the heads on line 55, Fig. 4. Fig. 6 is a transverse section on line 66, Fig. 3. Figs. 7, 8, and 9 are details.

The two interlocking heads of the automatic fluid-pressure coupling are constructed identically alike, and a description of one applies equally to the other, so that I shall describe the construction of one and refer to the similar parts of the other by similar letters of reference.

The coupling-head A is suspended beneath

the draw-bar W by means of two hangers X, which loosely embrace the head, and their legs are connected below the head to side bars x by means of bolts x', which bolts pass under the head and sustain it in position. The head lies on the bolts and is free to move up and down; but this vertical play is limited by means of bolts X', tapped into the heads and projecting through slots X² in the legs of the front hanger X, as shown. The hangers may be suspended directly from the draw-bar W, but preferably are suspended from a horizontal bar Z, which is fastened to the draw-bar by bolts Z', as shown, so that the head can swing laterally and longitudinally in relation to and beneath the draw-bar W, besides the vertical play in the hangers above mentioned. The hangers and head are normally pushed forward, so as to stand slightly in advance of the draw-bar W by means of the cushioning-spring z, which is contained in a tube z', the upper end of which is suspended from bar Z, as shown in Fig. 1, a plunger z² telescoping into the tube z' and connected to the rear ends of bar x, so that when the head is pushed backward spring z is compressed, and when the head is released the spring pushes the head forward, as will be obvious from the drawings.

The coupling-head has a female part A' and a male part A². The parts A' A² spring from a common body and lie side by side, and part A' of one head will fit pretty accurately into part A' of the opposite head. The outer end of part A' is flaring, as shown, and the outer end of part A² is provided with a hooked nose A³, as shown. The inner face of part A' is straight, vertical, and smooth, so that when coupled the parts A² of the couplers fit close against each other, Fig. 2. Part A² is hollow, and within it is a transversely-movable jointing-plug B, which has a beveled lug B' on its outer side which normally projects slightly beyond the outer face of part A² through an opening in the wall of the latter, Fig. 3. The jointing is normally pressed back by means of springs B⁴, fastened in the hollow part A² above and below the plug and pressing against lugs B⁵ on the top and bottom of the plug, as shown. Through the plug is a passage B², which extends from the inner side of the block

around to the rear side thereof and either communicates with a short flexible pipe C, which is tightly connected to a nipple B⁶ on the jointing-plug and to a nipple A⁷ at the 5 base of and within the part A², as shown, Fig. 2.

Around the mouth of the passage B² in inner face of the jointing-plug, Fig. 9, is a peculiar rubber gasket b, which is provided with 10 a lateral flange b' at its inner end, a lateral face flange b² at its outer end, and a flaring flange b³, extending inwardly from the edge of flange b². These flanges fit into corresponding recesses in the jointing-plug and, 15 constructed as shown and described, form a perfect gasket, which will prevent leakage of air around it and will withstand great pressure against flange b² and be capable of more wear and give better service than the ordinary forms of gaskets heretofore employed. 20 This gasket I consider very useful not only in the connection shown, but in other fluid high-pressure jointings.

The nipple A⁷ communicates with a passage-way A⁴, that extends back through the shank of the head and communicates with a transverse passage A⁵, which is connected at 25 one side of the head with the main pipe U of the ordinary fluid-pressure brake system or 30 heating system. At the other side of the head passage A⁵ is connected to a short pipe Y, which is provided with an ordinary fluid-pressure hand coupling-head y. This latter is to be used only in case of breakage of the 35 automatic coupling or when the opposite car is not provided with the automatic couplings. Passage A⁵ is provided with a hand-valve A⁶, by which communication with pipe Y is ordinarily closed.

40 An automatically-operated valve D is placed in passage A⁴, intermediate part A² and passage A⁵, this valve having an angular plate D' on its upper end, against the edge of which presses a spring D², which is adapted 45 to insure the full opening or closing of the valve and holds it so. To one corner of said plate, at the side opposite spring D², is pivoted the inner end of a valve-rod E, which extends forward through a suitable passage 50 a in the head, Figs. 2, 4, and 5, its front end overlying the socket in the inner end of part A', as shown, and being provided with a hook E', which is adapted to engage with the hooked nose A³ of part A² of an opposite coupling when it enters part A'. When rod E is 55 fully drawn out, Fig. 4, its hooked end rides upon a bevel a' at the front end of passage a, causing it to disengage the nose A³ at the proper time as it is being drawn outward by 60 the latter. A slot a² in the bottom of passage a permits the hook a' to engage with the nose A³.

On the inner end and upper side of rod E is a rearwardly-beveled lug E², for a purpose 65 hereinafter explained.

Attached to the under side of rod E and depending therefrom through slot a² is a pin

E⁴, which engages a slotted lug e' on the rear end of a slide e, which is fitted close to the inner face of part A² and is upheld and guided by means of flanges e², resting and guided in slots e³ in the face of part A², Figs. 4 and 9, or the plate may be attached to the face of part A² in any desired manner, so that it fits neatly thereagainst and can slide freely. 70 Preferably the face of part A² is recessed, as indicated in Fig. 2, so that when the coupling is effected and the plate moved back as far as it can go it is out of the way. 75

The main body of the plate is thin and flat 80 and one of its uses is to serve as a valve for closing the opening in the jointing-plug B when the heads are uncoupled, thus preventing dust entering and clogging the air-passage. When the heads are uncoupled, Fig. 85 3, the plate e projects over the opening in jointing-plug B and is held thereagainst by means of the pin E⁴ pressing against the lug e', as is evident from the drawings. When the heads come together in coupling, however, 90 the nose A³ strikes lug e' and pushes plate e backward, thereby, through pin E⁴, forcing rod E backward and opening valve D, as hereinafter described.

A spring E⁵ is placed in passage a over 95 rod E, so as to press the outer end of the latter down toward the lug e' and nose A³, then engage therewith, thus preventing hook E' disengaging the nose until hook E' strikes bevel a'. 100

F designates a rod lying beside rod E in a recess a⁴ in the top of part A² and projecting slightly beyond the center line of the jointing-plug B or beyond the rod E. (See Figs. 4 and 5.) This rod is pushed outwardly by 105 a strong coiled spring F⁶, surrounding it within recess a⁴.

The inner end of rod F is bent down, so as to lie close to plate D', and in it is formed a wide V-notch, the opposite sides F' F² of the 110 notch forming wedges, for the purpose hereinafter explained. The inner extremity of rod F is provided with a lug F³, which is adapted to be engaged by a bevel f' on a vertically-movable bar f, lying in a vertical 115 opening in the head at one side of passage A⁴ and in front of valve A⁶, as shown. The upper end of rod f is connected by a ball-and-socket joint f² to the lower end of a rod G, which extends up through a guide-bracket 120 Z², depending from bar Z, Fig. 2. The rod G also extends through a slotted clutch g, hinged to a clip or ring g', firmly secured to the lower end of the locking-pin W' of the draw-bar W, below which the head A is suspended. These parts are so arranged that when the locking-pin W' is raised, so as to release the locking-hook of the coupling W, clutch g grips rod G and pulls it up and with it bar f, which will cause bevel f' to engage 125 lug F³ of rod F and pull the rod backward if the parts are in the position shown in Fig. 2. 130

H designates a stiff flat spring lying athwart and above plate D' and the inner

end of rod F in position to be engaged by the lug E² on the inner end of rod E when the parts are in the position shown in Fig. 2. The function of spring H is to automatically open valve D in case of breakage of the couplings W or their pulling loose from the cars and the consequent pulling apart of heads A. The function of rod F is to keep spring H out of operative position, except in case of accident. This will be hereinafter explained.

Operation: Two opposite coupling-heads are suspended beneath two opposite draw-bars, the position of the interior parts of the heads A A being well indicated in Fig. 3. As the cars come together the male parts A² of the heads coincide with and enter the female parts A', and the noses A³, striking lugs e', push plates e back with rods E, thereby turning plates D' so as to open valves D. Simultaneously the jointing-plugs B B come opposite each other, and the lugs B', striking the flaring sides of the parts A', are forced inward toward each other, making an air-tight joint between the gaskets b, so that air passes from one head to the other. Simultaneously also rods F F strike each other and are both forced slightly backward, so that their lugs F³ lie above the bevels f' of bars f, the parts then being in the position shown in Fig. 2 and air circulating freely therethrough. The spring H, it will be observed, then lies in the bottom of the notch in rod F and in front of lug E² of rod E. Now if it is desired to uncouple the cars pin W', say, of the left-hand coupling is lifted, releasing the locking-hooks of couplings W and at same time lifting bar f, whose bevel f' catches lug F³ of rod F and pulls said rod to the left, so as to cause wedge F² to pass under spring H and lift it up out of the way of lug E² or rod E, so that the latter can pull the valve closed as the heads separate. This pull of rod F in the left-hand coupler-head A allows rod F in the right-hand head to be moved outward by its spring F⁶, so that spring H in said left-hand head is raised by its wedge F², so as not to interfere with the free outward movement of its rod E, which closes the valve in the right-hand head. As the heads separate, therefore, under these circumstances nose-hooks A³ engage hooks E', causing rods E to close valves D and plates e to close the jointing-plugs B B, which are separated instantly by the action of springs B⁴. When the locking-pin W' and rod f drop, rod F is freed from bar f and the parts are ready to couple again. Supposing the parts in the position shown in Fig. 2 once more and that the draw-bars break loose or some accident causes one car to break away from the other, the rods E will be pulled outward before or simultaneously with the outward movement of rods F, due to their springs. Consequently lugs E² on rods E will catch the springs H and tension them, and as soon as hooks E' are disengaged from noses A³ by the bevels a' springs

H will throw rods E back, opening the valves D and thus applying the brakes to the cars or train automatically.

Thus the coupling is automatic in coupling, in uncoupling, and in applying the brakes in case of accidental breaking apart of the train or heads.

Having thus described my invention, what I therefore claim as new, and desire to secure by Letters Patent thereon, is—

1. In an automatic fluid-pressure coupling, the combination of the opposite similar interlocking heads, each having a female portion and a hollow male portion, a jointing-plug in the male portion, springs for moving the jointing-plug outward; an air-passage in the head a valve in said air-passage; and a rod for operating said valve projecting forward in the female portion and adapted to engage the end of the male portion of the opposite coupling so as to open the valve when the heads interlock, and so as to close the valves when the heads disengage; and means for disengaging said rod from the male portion of the heads after the valve is closed, substantially as and for the purpose described.

2. In an automatic fluid-pressure coupling, the combination of the opposite similar interlocking heads each having a male and female portion substantially as described; an air-passage in the male portion, a jointing-plug in the male portion communicating with said air-passage, a rotary valve in said passage, a hooked rod for turning said valve projecting into the female portion and adapted to engage a hook on the end of the male portion of the opposite coupling; and a bevel for causing the rod to disengage the male portion after the valve is closed, substantially as and for the purpose described.

3. In an automatic fluid-pressure coupling, the combination of the opposite similar interlocking heads, each having a hollow male portion, a jointing-plug in the male portion, springs for moving the jointing-plug outward, a flexible pipe connection between the jointing-plugs and air-passage in the head; a valve in said air-passage; and a rod for operating said valve projecting forward in the female portion and adapted to engage the end of the male portion of the opposite coupling so as to open the valve when the heads interlock, and so as to close the valves when the heads disengage; and means for disengaging said rod from the male portion of the heads after the valve is closed; and means for separating the jointing-plugs laterally, as the heads separate, all substantially as and for the purpose set forth.

4. In an automatic fluid-pressure coupling, the combination of the interlocking heads, the air-passages therein, the valves in said passages, and means for operating said valves substantially as described; with a sliding plate or valve adapted to close the outlet of the air-passage in the heads when they are disconnected to prevent the entrance of

dust, &c., substantially as and for the purpose described.

5. In an automatic fluid-pressure coupling the combination of the interlocking heads, each having a male and female portion substantially as described, an air-passage in the male portion, a jointing-plug in the male portion communicating with the air-passage, a valve in said air-passage and means for operating said valve; with a sliding valve or cover for the outlet in the jointing-plug, means for moving it out of the way when the heads are coupled, and for moving it back to place when the heads are disengaged, substantially as described.

10. In an automatic fluid-pressure coupling the combination of the opposite similar interlocking heads, each having a hollow male portion communicating with the air-passage, a valve in said air-passage, a sliding cover for the outlet of the air-passage, and connections between said cover and valve whereby when the valve is opened the cover is withdrawn, substantially as and for the purpose described.

15. In an automatic fluid-pressure coupling, the combination of the interlocking similar heads each having a hollow male portion, a jointing-plug therein communicating with the air-passage in the body of the head, a main valve in said passage, a sliding valve or cover for the outlet of the plug; a sliding rod for operating said main valve having a pin engaging a slotted lug in said cover, whereby when the valve is opened the cover is drawn out of the way, all substantially as and for the purpose set forth.

20. In an automatic fluid-pressure coupling, the combination of the opposite similar interlocking heads each having a male and female portion substantially as described, an air-passage in the male portion, a jointing-plug in the male portion communicating with said air-passage, a rotary valve in said passage, a hooked rod for turning said valve projecting into the female portion and adapted to engage a hook on the end of the male portion of the opposite coupling; and a bevel for causing the rod to disengage the male portion after the valve is closed; with a valve for closing the outlet of the jointing-plug, and connections substantially as described, between said cover-valve and the said rod, all substantially as and for the purpose set forth.

25. In an automatic fluid-pressure coupling, the combination of the head provided with an air-passage, a valve therein a rod for operating said valve adapted to be actuated by the opposite head substantially as described, a spring adapted to open said valve if the heads are pulled apart accidentally, and means substantially as described, for keeping said spring out of action while the parts are in normal condition, for the purpose and substantially as described.

30. In an automatic fluid-pressure coupling, the combination of the head provided

with an air-passage, a valve therein, mechanism for opening and closing said valve automatically by the action of the opposite head in coupling and uncoupling; with means substantially as described, for automatically opening said valve if the heads are pulled apart because of accident, substantially as and for the purpose described.

35. In an automatic fluid-pressure coupling, the combination of the head provided with an air-passage, a valve therein, mechanism for opening and closing said valve automatically by the action of the opposite head in coupling and uncoupling; with means substantially as described, for automatically opening said valve if the heads are pulled apart because of accident, and means substantially as described for keeping said means out of operative position when the parts are in normal working condition, for the purpose and substantially as described.

40. In an automatic fluid-pressure coupling, the combination of the opposite similar heads each having a hollow male portion provided with an air-passage, a valve therein, the hooked rod as E for operating said valve adapted to be actuated by the opposite head; a spring H adapted to open said valve should the heads be accidentally pulled apart; a rod F adapted to prevent said spring engaging rod E when the parts are in normal working condition or relation; and a vertically-movable bar f, adapted to engage and shift rod F so as to cause it to throw spring H out of operative position when the devices are to be uncoupled in ordinary working, substantially as and for the purpose set forth.

45. In an automatic fluid-pressure coupling, the combination of the coupling-head having an air-passage, a rotary valve therein, a rod as E for operating said valve, a spring H adapted to engage rod E to open said valve; and a rod as F lying beside rod E and adapted to prevent spring H engaging the latter, for the purpose and substantially as described.

50. In an automatic fluid-pressure coupling, the combination of the coupling-head having an air-passage, a rotary valve therein, a rod as E for operating said valve, a spring H adapted to engage rod E to open said valve; and a rod as F lying beside rod E and adapted to prevent spring H engaging the latter; and the beveled bar f adapted to shift rod F so as to cause it to control spring H as described; with the locking-pin of the draft draw-bar, the clutch pivoted thereto, and the rod sliding through said clutch and connected to bar f, whereby bar f is raised with the locking-pin, all substantially as and for the purpose set forth.

55. The combination of the head having hollow male portion A², and female portion A', with the spring-retracted plug B in part A', a flexible connection between said plug and an air-passage in the body of the head, the valve D in said air-passage, the plate D' and hooked rod E for operating said valve,

all substantially as and for the purpose described.

16. The combination of the head having hollow male portion A^2 , and female portion A' , with the spring-retracted plug B in part A' , a flexible connection between said plug and an air-passage in the body of the head, the valve D in said air-passage, the plate D' and hooked rod E for operating said valve; with the sliding cover-valve e, having lug e' engaged by a pin on rod E, all substantially as and for the purpose described.

17. The combination of the head having hollow male portion A^2 , and female portion A' , with the spring-retracted plug B in part A' , a flexible connection between said plug and an air-passage in the body of the head, the valve D in said air-passage, the plate D' and hooked rod E for operating said valve; with the spring H, the double-beveled rod F for throwing said spring out of engagement with rod E, and means for operating rod F, all substantially as and for the purpose set forth.

18. The combination of the head having hollow male portion A^2 , and female portion A' , with the spring-retracted plug B in part A' , a flexible connection between said plug and an air-passage in the body of the head, the valve D in said air-passage, the plate D' and hooked rod E for operating said valve; with the sliding cover-valve e, having lug e' engaged by a pin on rod E; with the spring H adapted to engage rod E and close the valve, the spring-actuated double-beveled rod F underlying spring H and adapted to throw it out of engagement with rod E, and means for properly shifting rod F, all substantially as and for the purpose described.

19. The herein-described packing-ring b, having lateral flanges b^2 , provided with flaring flange b^3 , for the purpose and substantially as described.

20. The herein-described packing-ring b,

for the purpose described, having lateral flanges b^1 , b^2 , at its ends, and a flaring flange b^3 on the edge of flange b^2 , substantially as described.

21. The combination of the draw-bar, the plate Z suspended thereunder, the pair of swinging shackles X, X, suspended from said plate, the bars x connecting the shackles, the telescoping plunger and tube connecting bars x to the plate, and the cushioning-spring in the tube; with the fluid-pressure coupling supported in said shackles, and the bolts X' thereon engaging slots X^2 in the frontshackle, all substantially as and for the purpose set forth.

22. The combination of the opposite heads A each having a hollow male portion as A^2 and female portion as A' substantially as described; a valve D in the hollow passage in part A^2 , an angular plate D' on the valve D, and a spring D² pressing against the edge of said plate for throwing and holding the valve 65 fully open or closed, all substantially as described.

23. The combination of the head having hollow male portion A^2 , and female portion A' , with the spring-retracted plug B in part A' , a flexible connection between said plug and an air-passage in the body of the head, the valve D in said air-passage, the plate D' and hooked rod E for operating said valve, and the spring D² bearing against the edge 75 of said plate to throw and hold the valve fully open or closed, all substantially as and for the purpose described.

In testimony that I claim the foregoing as my own I affix my signature in presence of 80 two witnesses.

WILLIAM J. PUGH.

In presence of—

J. H. VAIL,

Wm. N. WALLACE.
